CLAIM

The ornamental design for a hat hanger as shown and described.

DESCRIPTION

FIG. 1 is a perspective view of the hat hanger of FIG. 2, shown attached to an environmental vehicle seat;

FIG. 2 is a top right side perspective view of a hat hanger, showing our new design;

FIG. 3 is a bottom left side perspective view thereof;

FIG. 4 is a left side view thereof;

FIG. 5 is a right side view thereof;

FIG. 6 is a front view thereof;

FIG. 7 is a rear view thereof;

FIG. 8 is a top view thereof; and,

FIG. 9 is a bottom view thereof.

The broken lines showing the vehicle seat in FIG. 1 depict unclaimed environment only and form no part of the claim, and all other broken lines depict portions of the hat hanger that form no part of the claim.

1 Claim, 9 Drawing Sheets
